SET-UP TABLE

William L. Valiquette, Dayton, Ohio, assignor to
 Harris-Seybold-Potter Company, Cleveland,
 Ohio, a corporation of Delaware

Application June 17, 1935, Serial No. 26,985

10 Claims. (Cl. 164—59)

This invention relates to improvements in set-up tables, particularly set-up tables for spacing machines. For example, the invention may be employed in connection with paper cutting machines having spacing means for locating the various cuts. The invention however would be entirely applicable for use in connection with machines for boring or punching holes at given positions in a sheet, strip or bar, or for performing other work at predetermined intervals upon sheets, strips or bars of various materials.

One of the objects of the present invention is the provision of auxiliary set-up means which may be employed to properly locate and fix points of operation along a stop bar, which bar may then be transferred bodily to the operating machine to control the spacing movements of the machine, whereby the set-up for one job may be accomplished while the previous job is being performed in the machine, thereby conserving the operating time of the machine, reducing the overhead accordingly, and enabling a shop to turn out a given amount of work with fewer machines than would be required otherwise.

Another object of the invention is the provision of means for making a set-up of a stop bar outside of the machine in which it is to be used, where the stops act to control, that is to open or close, an electric control circuit.

Other objects and features of novelty will appear as I proceed with the description of that embodiment of the invention which, for the purposes of the present application, I have illustrated in the accompanying drawings, in which

Fig. 1 is a plan view of the set-up table with a stop bar mounted therein.

Fig. 2 is an end view of the table and associated parts.

Fig. 3 is a fragmental front elevational view showing contacts on the carrier in operative position with respect to a stop on the stop bar.

Fig. 4 is a front view of a fragment of the stop bar with stops thereon.

Figs. 5 and 6 are cross sectional views taken substantially on the lines 5—5 and 6—6, respectively, of Fig. 4.

Figs. 7 and 8 are detail sectional views taken substantially on the lines 7—7 and 8—8, respectively, of Fig. 1.

Fig. 9 is a horizontal sectional detail view on a larger scale taken substantially on the line 9—9 of Fig. 3.

Fig. 10 is a vertical sectional view on a larger scale taken substantially on the line 10—10 of Fig. 4.

Fig. 11 is a plan view of a sheet of paper with the lines of cut marked thereupon to illustrate the character of work which may be done upon a paper cutting machine in connection with which the present invention may be employed.

Referring to the drawings, I provide a table 10 which may be supported on suitable legs (not shown) or may be supported upon a bench. This table is adapted to support a whole work sample which is represented at 11. Where the invention is used in connection with a paper cutting machine, this work sample will consist of a strip of paper taken from one of the sheets which are to be cut up in the machine. The lines of cut are indicated on the work sample by the dot and dash lines *a* and *b*. The work sample is lined up against a side gauge 12 and caused to abut against an end stop 13. The latter corresponds in position to the rearmost position of the back gauge of a paper cutting machine. When the work sheet has been properly positioned in this manner it is held against movement by a clamp, which comprises a long bar 14 that is carried by the ends of two arms 15, each of which is pivotally mounted in rearwardly extending ears 16 of the table. When the clamp is not in use it may be swung backwardly out of the way.

In the table 10, forward of the side gauge 12, I form two guide grooves or ways 17 and 18, the groove 17 being dove-tailed, and the groove 18 having outwardly flared sides. These grooves are parallel to each other and to the side gauge 12. 19 is a bracket which is adapted to slide in these grooves. It may be locked in any desired position of adjustment by set screws 20 which take into a dove-tailed clamping bar 21 running in the groove 17. A depending rib 22 forming an integral part of the bracket runs in groove 18 and assists in holding the bracket in proper alignment. At its forward end bracket 19 carries a cone pointed pin 23 similar to the dead center of a lathe. A second cone pointed pin 24 is carried by an arm 25 projecting forwardly from the opposite end of table 10. The pin 24 however is adjustable in the arm 25, being threaded to receive nuts 26 and 27 which may be tightened to lock the pin 24 against movement. The pins 23 and 24 are in alignment and their axis is parallel with grooves 17 and 18 and with side gauge 12. They are adapted to receive a stop bar 28 which in the present instance is shown as of square cross section, having conical cavities in its extremities for the reception of the pins 23 and 24. In each side of the bar 28 there is a groove 29 with flaring sides and a dove-tail groove 30. The stop bar

may be held in any one of four different angular positions by a lever 31 mounted in the bracket 19, which lever has a projection 32 adapted to take into any one of the four grooves 30. A coil spring 33 serves to hold the lever yieldably in operative position.

Each side of the bar 28 is adapted to receive a set of stops corresponding to a series of cuts in a paper sheet. In accordance with the present disclosure there are certain major stops A and certain auxiliary stops B. The stops A are used for the principal cuts, indicated at *a* on Fig. 1, while the stops B mark the trim-out cuts, indicated at *b* on Fig. 1. Stops A are mounted directly upon the bar 28. They each have integral projections 34 running in grooves 29 and carry separate dove-tail clamping pieces 35. The latter are operated by screws 36 which extend through smooth bores in the stop members A and into threaded openings in the clamping pieces 35. When the screws 36 are loosened the stops may be slid along the bar to any desired position, and when the proper position of adjustment is reached the screws 36 are tightened to lock the stops in place. Each stop A carries a disk 37 of metal which is preferably insulated from the remainder of the stop by a fiber washer 37', see Fig. 10.

Each stop A has two threaded holes 38 therein, in either one of which a screw 39 may be mounted. Across the face of the stop there is also a groove 40. Auxiliary stop B has a rearwardly extending rib 41 fitting the groove 40, and a slot 42 adapted to receive the screw 39. By projecting the screw 39 through the slot 42, setting it in one or the other of the two holes 38, and by moving the stop B laterally within the limits permitted by the slot 42, any desired spacing of the two stops with respect to each other may be effected. Stop B at its upper end carries a metal disk 43 which is preferably insulated from the rest of the stop, as in the case of disk 37, and is of the same size and shape as disk 37 but, as will be noted from Fig. 6, is situated in a plane forward of the plane of disk 37. Stops B are used only when two stop positions are closer together than the shortest possible spacing of two stops A.

On the track provided by guides or ways 47 and 48, and to one side of the bracket 19, I mount a carrier 45 which is movable along the said track in the same way as bracket 19, being provided with the same kind of groove engaging elements, and being adapted to be locked in any desired position of adjustment by a set screw 46.

The carrier is provided on its rear side with a transverse beveled rule or position indicator 47 which runs over the side gauge 12 and over the edge of the work sample 11. By means of this position indicator the carrier 45 may be brought into accurate register with any desired line of cut on the work sample. The carrier 45 may carry a pair of dry cells 48 and 49 and an electric signal, such as a lamp 50. The carrier also includes a forwardly extending arm 51 in which is supported a pivot pin 52. On the latter there are oscillatably mounted two arms 53 and 54. Coil springs 55 and 56 tend to depress the outer ends of these arms, but their movement in that direction is checked by stop screws 57 which are mounted 70 in a bar 58 extending forwardly from the arm 51.

The arm 53 carries a pair of spaced metal contacts 59 and 60, supported upon bolts 61 and 62, which are insulated from the contacts by fiber washers 63. If desired, the latter may be held 75 against rotation by locking pins 64, and the disks

59 and 60 may be held against turning movement by being locked to the washers 63 by means of key 65. When the disk 37 of stop A is brought into precisely the proper position the two contacts 59 and 60 engage the disk 37 simultaneously 5 and are thereby electrically connected. As soon as there is any relative movement of the slide with respect to the stop however the engagement of one of the contacts 59 and 60 with the disk 37 is interrupted and the electrical connection between 10 the two contacts is broken.

The arm 54 supports two spaced contacts 66 and 67 which are mounted and insulated in the same manner as the contacts 59 and 60. They are adapted to engage the disk 43 of a stop B and to 15 be thereby connected electrically in the same manner as above described with respect to the contacts 59 and 60.

The two contacts 60 and 67 have flexible leads 68 and 69 soldered thereto. These leads are connected in parallel with an electric conductor 70 which may extend to one terminal of the electric lamp 50. From the other terminal of this lamp a conductor 71 extends to the battery cell 48. A short conductor 72 connects the two cells 48 and 49, and a further conductor 73 extends from cell 49 back to another pair of flexible leads 74 and 75 which are soldered to the contacts 59 and 66, respectively. Obviously, therefore, if either the rear pair of contacts 59 and 60 are electrically 30 connected together by a disk 37, or the forward pair 66 and 67 are connected by a disk 43, the circuit through the battery and the lamp 50 will be completed and the lamp will be lighted.

Operation.—In order to explain the operation 35 of the present apparatus, let us assume that we have a large quantity of sheets of paper, each sheet having printed thereupon a considerable number of labels or the like, as indicated by the division lines in Fig. 11. The first step in proceeding to set up the job for operation upon a spacing and cutting machine, is to place a number of stops A upon each of four sides of a stop bar 28, and mount the bar between the pin centers 23 and 24. Then the operator removes a strip of 40 paper from a sample sheet by cutting it along a line located somewhat as is the dot and dash line 76. This strip of paper is then placed upon the set-up table in the position of the work sample 11 of Fig. 1, with the edge 77 adjacent the side 50 gauge 12 and the edge 78 against the end stop 13. The operator then loosens set screw 46 and moves the carrier 45 along its track until the edge of 45 position indicator 47 comes directly over the first cut line 79a. He now turns down set screw 46 to 55 lock the slide in that position temporarily. The operator then moves the foremost stop A on the forward side of bar 28 until its disk 37 comes directly between the contacts 59 and 60, when the lamp 50 will be lighted. The arms 53 and 60 55 are permitted to yield, or swing upwardly, as the disk 37 of the stop moves under one of the contacts 59 and 60. The operator thereupon tightens screw 36, which secures the stop in that position. Next he again loosens screw 46 and 65 moves carrier 45 to the left until position indicator 47 registers with the next cut line 80a, when the carrier is locked to the table. The lamp 50 of course goes out at the time movement of the carrier begins. The next stop A on the forward 70 side of the bar 28 is now moved forward until its disk 37 completes the electric circuit, again lighting the lamp 50, when the stop is locked to the stop bar. The next cut line 81b is situated only a short distance from the cut line 80a, and this 75

distance being less than the width of a stop A, it is impossible to employ a stop A to define or mark the cut line 81b. The operator moves the carrier 45 to cause the position indicator 47 to register with line 81b. He then mounts a stop B on the A stop last mentioned, and while the screw 39 is loosened, moves the stop B along until it bridges the contacts 66 and 67 on the forward arm 54, whereupon the electric circuit is completed and the lamp 50 is energized. The screw 39 is now tightened down, locking this stop B in place. The operator then proceeds in like manner to set a stop A for cut line 82a and a stop B for cut line 83b.

The operator now takes another sample sheet, and cuts it on the lines 79a and 80a and places it on table 10 in the position heretofore described, with the edge 79a against the side gauge 12. He then presses down on lever 31 and turns the bar 28 through a quarter revolution, bringing a new side thereof into position beneath the arms 53, 54 and their contacts. The carrier 45 is then moved to the right hand end of the table and is set to register successively with cut lines 84a, 85a, 86a, 87a, 88b, and 89a. This completes the set-up for another series of cuts to be made upon the spacing and cutting machine.

In a similar manner the stop bar is turned through a further quarter revolution, a new work sample consisting of a strip of paper cut along the lines 81b and 82a is placed in position on the table, and stops are set on the stop bar corresponding to the cut lines 90a, 91b, 92a, 93b, 94a and 95b, after which the stop bar is again turned through a quarter revolution, a new strip of paper with side edges 83b and 78 is placed on the table and stops set for the cut lines 96a, 97a, 98a, 99a, 100a, and 101a, it being understood that stops A are used to correspond with all of the cut lines on the drawings marked with the suffix a, while stops B are used to correspond with all of the cut lines marked with the suffix b.

The stop bar is now set up for four different complete series of cuts, which is sufficient to handle all of the work of cutting labels from the sheet illustrated in Fig. 11. The position of any given cut is noted on the scale 12. The stop bar is now removed from the set-up table and mounted in a spacing and cutting machine, after which it is adjusted longitudinally until the noted cut comes at a point on the scale of the cutting machine which corresponds to the noted point on the set-up table. No other adjustment is necessary. With the stop bar in the proper angular position in the cutting machine, all of the sheets are run through the machine to make the cuts 79a, 80a, 81b, 82a, and 83b, which results in three sets of paper strips.

The stop bar 28 is then turned through a quarter revolution in the machine, and the stops for cutting the lowermost strip, as viewed in Fig. 11, are brought into operative position. All of these lowermost strips are now put through the machine. Next the stop bar is turned through another quarter revolution and the next set of strips are cut into their ultimate pieces, after which the stop bar is again rotated and all of the strips of the last set are cut up.

Of course it may not always be possible to obtain the necessary set-up for a given job with four sets of cuts, and in such cases more than one stop bar will have to be employed. In some cases also it may be advisable to use a stop bar 75 which is formed to receive one set of stops only,

or one which is formed to receive a plurality of sets other than four.

It will also be apparent that my set-up table can be employed for setting up work to be performed on different sizes of cutting machines, since stop bars 28 of different lengths may be accommodated by merely moving the bracket 19 along its track to the desired position.

Furthermore, the invention in its broader aspects contemplates relative movement broadly 10 between the carrier 45 on the one hand and the work sample and stop bar on the other hand. That is to say, the carrier 45 may be made stationary if desired, while the holder for the work sample and the mounting for the stop bar may 15 be caused to move together past the carrier 45.

Variations from the described structure may be employed. Accordingly I desire it to be understood that the scope of the invention is to be regarded as defined by the appended claims rather 20 than by the foregoing description and the accompanying illustrations.

Having thus described my invention, I claim:

1. A set-up table for spacing machines upon which a set-up may be made independently of the spacing machine and then transferred to the spacing machine, comprising a support for removably holding a stop bar at its ends and a work sample parallel to said bar, a carrier, means for producing relative travel of the carrier and support in a path parallel to the bar, said carrier having a position indicator adapted to run along said work sample, a series of stops adapted to be fixed to said stop bar at selected points, and means upon said carrier for indicating the stop 35 position on said stop bar corresponding to any given position of said position indicator with respect to the work sample.

2. A set-up table for spacing machines upon which a set-up may be made independently of the spacing machine and then transferred to the spacing machine, comprising a support for removably holding a stop bar at its ends and a work sample parallel to said bar, a carrier, means for producing relative travel of the carrier and support in a path parallel to the bar, said carrier having a position indicator adapted to run along said work sample, a series of stops adapted to be mounted on said stop bar at selected positions and to have sliding movement longitudinally of 50 the bar for adjustment purposes, an electric signal, and means on said carrier for energizing said signal when a stop is moved into a predetermined position with respect to the carrier.

3. In a set-up table of the character described, a support for holding a stop bar at its ends comprising centers upon which the bar may be revolved to any one of a plurality of different positions, means for holding the bar in any one of said positions, said bar having stop retainers thereon corresponding in number to the number of said different angular positions, said retainers being adapted to slidably support stops, means on said support for holding a work sample in a fixed position parallel to said bar, a carrier, means for producing relative travel of the carrier and support in a direction parallel to the bar, means for retaining the support and carrier in any given position of relative adjustment, said carrier having a position indicator adapted to run along said work sample, a series of stops adapted to be fixed in each of said retainers at any desired points, and means upon said carrier for indicating the stop position on said stop bar corre- 75

sponding to any given position of said position indicator with respect to the work sample.

4. A set-up table for a spacing machine upon which a set-up may be made independently of the spacing machine and then transferred to the spacing machine, comprising a support for holding a sample of work and for removably holding a stop bar in parallelism with the work sample, a carrier having position indicating means overlying the work and the stop bar, and means for producing relative travel of the carrier and support in a direction parallel with said bar, whereby stops may be located on the stop bar corresponding with given positions on the work sample.

15 5. A set-up table for a spacing machine, comprising a support for a sample of work, a support for removably holding a stop bar in parallelism with the work sample, and a carrier movable in a path between the work sample and stop bar parallel to the latter, said carrier having position indicating means overrunning the work support, an electric signal circuit, said carrier having electrical means adapted to cooperate with stops on the stop bar to control said signal circuit, whereby the stops may be located in positions corresponding with given points upon the work sample.

20 6. A set-up table for a spacing machine, comprising a support for a sample of work, a support for removably holding a stop bar in parallelism with the work sample, and a carrier movable in a path between the work sample and stop bar parallel to the latter, an electric signal carried by the carrier, an electric circuit for said signal, said carrier having position indicating means overrunning the work support, a pair of spaced contacts carried by the carrier connected with said circuit, whereby the said contacts may be caused to engage upon opposite sides of a metallic part of a stop when the latter is moved to the proper position along said stop bar, the energization of the said signal indicating that the desired position of adjustment of a stop has been reached.

25 7. A set-up table for a spacing machine, comprising a support for a sample of work, a support for removably holding a stop bar in parallelism with the work sample, and a carrier movable in a path between the work sample and stop bar parallel to the latter, said carrier having position indicating means overrunning the work support, an electric signal circuit; a pair of spaced contacts carried by the carrier overlying said stop

bar and connected with said circuit, and means for yieldably mounting said contacts, whereby the said contacts may be caused to engage upon opposite sides of a metallic part of a stop when the latter is moved to the proper position along said stop bar, and whereby the said contacts may ride over a stop when the carrier is moved along to another position.

8. A set-up table for spacing machines upon which a set-up may be made independently of the spacing machine and then transferred to the spacing machine, comprising a support for holding a sample of work and for removably holding a stop bar in parallelism with the work sample, a carrier mounted upon said support independently of the stop bar, said carrier being movable lengthwise of the table in a direction parallel with the stop bar, and having position indicating means overlying the work support and the stop bar, and stops adjustable lengthwise upon the stop bar to assume positions on the bar indicated by said position indicating means.

10 9. A set-up table for spacing machines upon which a set-up may be made independently of the spacing machine and then transferred to the spacing machine, comprising a support for holding a stop bar and a sample of work, a carrier mounted to travel upon said support in a direction parallel with said stop bar, said stop bar being removable from the support without disturbing the carrier, and said carrier having position indicating means overlying the work support and the stop bar, and stops adjustable lengthwise upon the stop bar to assume positions on the bar indicated by said position indicating means.

15 10. A set-up table for spacing machines upon which a set-up may be made independently of the spacing machine and then transferred to the spacing machine, comprising a support for holding a sample of work and for removably holding a stop bar in parallelism with the work sample, a carrier mounted upon said support independently of the stop bar, said carrier being movable lengthwise of the table in a direction parallel with the stop bar, said carrier having position indicating means overlying said work support, stops adjustable lengthwise upon said stop bar, means on said carrier adapted to embrace one of said stops, whereby the stop may be moved lengthwise upon the bar by the movement of the carrier, and means for locking the stops in adjusted position.

30 35 40 45 50 WILLIAM L. VALIQUETTE.
